UNITED STATES PATENT OFFICE

2,244,011

BOAT HULL CONSTRUCTION

Dean B. Johnson, La Mesa, Calif., assignor to San Diego Marine Construction Co., San Diego, Calif., a corporation of California

Application June 10, 1939, Serial No. 278,516

5 Claims. (Cl. 114—65)

My invention relates to the construction of the portion of the hull of a wooden boat near the keel and the objects of my invention are:

First, to provide storage space in the bottom of the hull of wooden boats in substitution for the floor timbers, kelsons, sister kelsons and engine bearers made of reinforced metal;

Second, to provide a construction of this class which conserves the space in the extreme lower side of wooden boat hulls for storage or like purposes;

Third, to provide an assembly construction of this class which reinforces and strengthens the wooden hull boat at its most vital portion;

Fourth, to provide a construction of this class which is applicable for use in connection with various types of wooden hull boats;

Fifth, to provide a construction of this class in which the space usually occupied by the floor timbers, kelsons, sister kelsons and engine bearers is divided up into a plurality of storage spaces for fuel supply or the like separated by substantial longitudinal and transverse reinforcing, vertical partitions;

Sixth, to provide a construction of this class in which metal kelsons are substituted for the floor timbers in the wooden hull boats; and

Seventh, to provide a construction of this class which is very simple and economical of construction, easy to install, efficient in its action or which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a longitudinal sectional view of my novel boat hull construction taken from the line 1—1 of Fig. 2 showing some of the portions in elevation to facilitate the illustration; Fig. 2 is an enlarged transverse sectional view taken from the line 2—2 of Fig. 1.

Similar characters of reference refer to similar parts and portions throughout the views of the drawing.

The keel 1, shoe 2, garboard planking 3, general hull planking 4, bottom metal plate 5, upper metal plate 6, longitudinal vertical plates 7, 8 and 9 and transverse baffle plates 10 constitute

the principal parts and portions of my boat hull construction.

The keel 1 is of conventional wooden keel construction and it is faced with the conventional shoe 2 of reinforcing metal plate. The base planks 3 and hull planking 4 are also of conventional type. The lower ones on opposite sides, however, are secured to a steel bottom plate 5 which is provided with a straight portion 5a which rests longitudinally on the upper side of the keel 1 and extends aft to near the stern of the boat and forwardly to near the bow of the boat. It is provided with inclined portions 5b and 5c conforming to the angle of the boat bottom from the keel outwardly on opposite sides, as shown best in Fig. 2 of the drawing. Secured substantially horizontally across from the member 5b to the member 5c some distance above the portion 5a is the upper metallic plate 6 leaving a large storage space substantially the full length of the boat between the lower plate 5 and the upper plate 6.

Positioned longitudinally of the boat hull and centrally of the portion 5a in a vertical position is a middle vertical longitudinal partition 7 which extends from the portion 5a at its middle to the middle of the upper metal plate 6, shown best in Fig. 2 of the drawing, which forms a reinforced baffle and compartment partition. On opposite sides of this plate 7 in spaced relation therefrom substantially intermediate said plate 7 and the side edges of the plate 6 are other longitudinal vertical plates 8 and 9 which extend longitudinally in vertical position between the members 5b and 5c and the plate 6 forming further reinforcing and compartment partitions extending substantially the full length of the boat hull.

Positioned transversely in the space between the bottom metal plate 5 and the upper metal plate 6 and extending between the partitions 7, 8 and 9 forming a large number of separate compartments are the transverse baffle plates 10 shown best in Fig. 1 of the drawing.

It will be here noted that the compartments formed separately by the lower plate 5, upper plate 6, partitions 7, 8, 9 and baffle 10 may be utilized for various purposes such as fuel for operating the boat or for any kind of storage purposes and it is obvious that these storage products may be shifted from one compartment to another for maintaining the best equilibrium, both thwart ship and fore and aft as desired; and that the upper plate 6 serves the same function as the upper side of the floor timbers, kel-

sons and engine bearers of the conventional wooden hull boat and may be made of ample strength and provide effective storage space.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a boat hull construction of the class described, the combination of a wooden keel, wooden planking, a metallic plate supported across the upper side of said keel and diverging upwardly in opposed direction in angular V-shaped form on opposite sides of said keel and forming the support for said wooden planking, and a substantially horizontal plate connected therewith at its side extremities and extending longitudinally of the keel.

2. In a boat hull construction of the class described, the combination of a wooden keel, wooden planking, a metallic plate supported across the upper side of said keel and diverging upwardly in opposed direction in angular V-shaped form on opposite sides of said keel and forming the support for said wooden planking, a substantially horizontal plate connected therewith at its side extremities and extending longitudinally of the keel, and a plurality of longitudinal substantially vertical varying depth partitions connecting said first mentioned angular plate with said substantially horizontal plate.

3. In a boat hull construction of the class described, the combination of a wooden keel, wooden planking, a metallic plate supported across the 40 upper side of said keel and diverging upwardly

in opposed direction in angular V-shaped form on opposite sides of said keel and forming the support for said wooden planking, a substantially horizontal plate connected therewith at its side extremities and extending longitudinally of the keel, a plurality of longitudinal substantially vertical varying depth partitions connecting said first mentioned angular plate with said substantially horizontal plate, and a plurality of transverse baffle partitions connected therewith between said angular and longitudinal plates and forming a plurality of separate enclosed varying sized storage compartments.

4. In a boat hull construction of the class described, the combination with a wooden boat hull with a wooden keel of metallic kelsons and engine support formed of hollow storage compartments including a substantially horizontal metallic upper plate, an angular V-shaped lower plate with a substantially horizontal middle portion resting on said wooden keel and a plurality of vertical reinforcing partitions connected therewith and extending from said upper plate to said lower plate.

5. In a boat hull construction of the class described, the combination with a wooden boat hull with a wooden keel of metallic kelsons and engine support formed of hollow storage compartments including a substantially horizontal metallic upper plate, an angular V-shaped lower plate with a substantially horizontal middle portion resting on said wooden keel and a plurality of vertical reinforcing partitions connected therewith and extending from said upper plate to said lower plate, said reinforcing partitions extending both longitudinally of the boat and transversely thereof and said angular V-shaped lower plate with the horizontal portion forming the support for the keel and wooden hull.

DEAN B. JOHNSON
